Attest.

UNITED STATES PATENT OFFICE

LOUIS ERWIN D'ARX, OF CLAYFIELD, BRISBANE, QUEENSLAND, AUSTRALIA

VENETIAN BLIND

Application filed February 21, 1929, Serial No. 341,730, and in Australia August 2, 1928.

This invention relates to Venetian blinds for use on verandahs and such like places where it is desired to control light and ventilation, the object being to provide a strong blind which can be supplied at a reasonably low cost, which is strong, and which may be closed or opened to any desired degree.

In carrying out my invention I provide a number of uprights, each of which carries a number of levers arranged one above the other and hingedly connected vertically by a number of rods. Horizontal slats are secured to the outer ends of the levers. Means are provided for operating the blind and securing it in any desired position.

In order that the invention may be better understood, I will now describe it with the aid of the accompanying drawings, in which

Fig. 1 is a part perspective view (part in section).

Fig. 2 is a part perspective view with certain parts in different relative positions.

Fig. 3 is a part end view.

Fig. 4 is a part plan.

The uprights A are arranged in pairs, a number of levers B, arranged one above the other, being pivotally carried between the uprights forming each pair. The uprights A are secured at the upper and lower ends. The levers B are, at their inner ends, hingedly connected by vertical rods C, and the forward ends carry horizontal slats D, which are secured thereto by screws or other means. The slats D may be half rounded on the outer edge.

The uprights A have rebates E, and, when the blind is closed, the rods C fit neatly into them, thus allowing the levers B to lie flat against one another and the nose of one slat 40 D to lie on the rear portion of the slat D immediately below it.

The blind is opened and closed by the handles F, which are pivoted to, say, the centre pair of uprights A and to the vertical rods C. A grip G is provided between the inner ends of the handles F.

The blind is held in any desired position by the pawl H, the end of which engages notches J in the uprights A. Single uprights A and vertical rods C may be used

instead of pairs, if desired, and the numbers of uprights or pairs of uprights would be according to the width of the blind.

It is advisable to connect the heads of the rods C by a horizontal rail to ensure that they all operate in unison.

The whole or any part of the blind is of wood and/or metal, as desired, but I find that the former material is suitable for general purposes. The shape and construction of the various parts may be varied as found desirable and according to the material used and the size of the blind.

Having now particularly described and ascertained the nature of my said invention and in what manner the same is to be performed, I declare that what I claim is:

1. An improved Venetian blind consisting of a number of uprights, levers pivoted thereon one above the other, vertical rods 70 hingedly connected to the ends of said levers, horizontal slats secured on the other ends of said levers, said uprights having rebates to receive said vertical rods when said blind is closed.

2. In a Venetian blind including uprights having downwardly facing notches, levers pivoted to said uprights, one above the other, vertical rods connected to the ends of said levers, and horizontal slats secured on the other ends of the levers, a handle member pivotally connecting one of the uprights and one of the rods, and a pawl pivotally connected at the pivotal connection between the handle member and rod, and engaging said notches to retain the blind in adjusted position.

In testimony whereof I affix my signature.

LOUIS ERWIN D'ARX.
